UNITED STATES PATENT OFFICE.

ANTHONY VANDERVELD, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

SHOW CASE ROTATING DISPLAY RACK.

Application filed December 15, 1924. Serial No. 755,860.

This invention relates to rotating display racks which are used in show cases or wardrobes, and in which two spaced apart parallel bars are included in the rack structure 5 on which garments may be hung. The show case or wardrobe is longer than it is deep and when the rack is located within the case or wardrobe the bars must be held in parallel relation to the back of the case. The 10 rack is mounted for movement bodily forward to a position at the front of the case, at which position it can be turned or rotated so that either rod, carrying a line of garments, may be presented to the front for 15 display and inspection, or removal of the garments.

In constructions of this kind it is necessary, in order to prevent destructive engagement of the ends of the rack rods with the 20 back of the case, that the rack shall be held from rotation when it is within the case or at any position except extreme front position; and it is necessary that the holding means shall become ineffective when the rack 25 has reached its extreme front position so that the rack can be rotated. It is also necessary, when the rack has been rotated after it has reached extreme front position, that it shall be locked against any bodily movement rearward into the case or wardrobe, this being 30 particularly true of glass show cases, as such bodily movement, when the rack has been rotated, would cause the inner ends of the garment holding rods to strike 35 against, break and pass through the back of the show case.

The present invention is directed to improvements over the construction shown in my Patent No. 1,113,386, issued October 13, 40 1914 relating to the same general subject matter. This invention, while securing all of the advantages set forth in the patent aforesaid, has also other advantages of simplicity of construction and of reliability in 45 action particularly with respect to the means used for effecting the locking of the rack against rotation when at any other position except extreme front position and also locking the rack from rearward bodily movement 50 at any time that the rack is rotated or when the garment holding rods are away from a position parallel to the back of the case.

For an understanding of the invention and the constructions embodying the same, 55 reference may be had to the following description taken in connection with the accompanying drawings in which:—

Fig. 1 is a plan view of the rack, the show case in which it is installed being 60 shown in horizontal section with the floor thereof removed, the rack being shown in full lines and partially rotated at its front position in the case and being indicated in dotted lines in the position which it occupies when within the case. 65

Fig. 2 is a vertical section centrally of the show case and of the rack located therein.

Fig. 3 is a fragmentary plan view with parts broken away and in section, illustrating the locking of the rack carriage when at its front position, this locking being against rearward bodily movement of the rack and accomplished by a rotation of the 70 rack from normal position, and 75

Fig. 4 is a similar plan view illustrating the position of the parts of the mechanism which hold the rack against rotative movement when within the case or in at any position except extreme front position. 80

Like reference characters refer to like parts in the different figures of the drawings.

The show case, indicated at 1, includes a top 2, ends 3 and back 4 of glass. As shown in the drawings the front of the show case 85 is open, but this is adapted to be closed by suitable doors, which are not shown, so as to permit opening of the show case for access thereto. The bottom 5 of the show case rests on the floor of the store in which it 90 is installed and a short distance above the same a floor 6 is secured horizontally and paralleling the bottom. Between said bottom 5 and the floor 6 the supporting carriage for movably carrying the rotating 95 rack may be located and covered from view by the floor 6.

The carriage is mounted for bodily movement toward and from the front of the show case on parallel spaced apart tracks 7 of 100 channel iron which extend from the front to the rear of the case, as shown. These tracks 7 are re-inforced and strengthened by additional channel iron members 8, the webs of which are backed against the webs of the channel 7 and permanently secured thereto 105

by spot-welding, riveting or in other suitable manner. Rollers 9 on the ends of shafts or axles 10 are designed to traverse the channels 7, said rollers and the shafts or axles therefor being disposed below and serving to carry the frame 10 of the carriage 11 which is of the form and structure shown.

10 Adjacent the front portion of the carriage frame 11 a pedestal is secured including a base 12 which is bolted to the frame from which a tube 13 extends vertically somewhat more than half way to the top 2 of the show case. A rod 14 extends downwardly through the tube 13 and the base 12, 15 at its lower end having a circular disk 15 rigidly attached in diametrically opposed sides of which substantially semicircular recesses 15^a are made. In the lower end of the rod 14 a hardened pin 16 is fixed, its 20 lower end bearing against a hardened plate 17 which is located in a suitable recess in the upper side of the carriage frame 11. This permits a substantially frictionless turning of the rod 14 and the rack carried at 25 the upper end thereof.

At the upper end of the rod 14 and above the tube 13 a garment holding rack is secured including a head 18 fixed to the rod 14 from which arms 19 extend in opposition 30 to each other. Two rods 20 are fastened to the ends of the arms 19 one at each side of the head. These rods are thus spaced apart and are located parallel to each other. The rods are spaced a distance sufficient that 35 garments held on the usual garment hangers may be suspended from the rods and not interfere with each other; and when the carriage is at its rearmost position in the case and the rods parallel to the back of the case, the case is substantially filled with 40 the garments held on the rods. In order to permit the passage of the base 12, which extends through the floor 6 in the bodily movement of the rack toward and from the 45 front of the case, a slot 21 is cut in said floor 6 which the base 12 may traverse in its movements.

On the carriage frame 11 at one side of 50 and a short distance in front of the rod 14 a bell crank lever is pivotally mounted at 22. This lever has an arm 23 normally extending directly back from the pivot 22, at its free end equipped with a roller 24 which is adapted to seat in either of the recesses 55 15^a of disk 15. The other arm 25 of the bell crank lever extends outwardly substantially at right angles to the arm 23. A link 26 is pivotally connected at one end to the arm 25 between its ends and together with a second 60 superimposed link 27 is pivotally connected to one end of a short link 28 which, at its opposite end, is pivotally connected to the carriage frame 11; as best shown in Figs. 3 and 4. The link 26 extends over the arm 65 25 and at its free end a strong coiled spring

29 is secured at one end, the opposite end of said spring being secured to the relatively stationary carriage frame 11.

Near the free end of the arm 25 of the bell crank lever a roller 30 is mounted which is 70 in engagement with a locking member 31 pivotally mounted at 32 on the carriage frame. The locking member 31 is of irregular shape and has a suitably formed recess 33 on its inner side in which the roller 30 75 may seat; and in front of said recess is formed with an inner edge 34 slightly curved against which the roller 30 bears in certain positions of the rotatable rack. The locking member 31 is formed with a 80 projecting portion extending inwardly from the pivot 32 between which and the carriage frame 11 a coiled spring 35 of less strength than the spring 29 is interposed, the tendency of the spring being to turn the locking member inwardly about its pivot 32. At 85 its outer edge the locking member 31 is formed with two spaced apart projections, a finger 36 adjacent the front end of the member, and a hook 37 adjacent its rear end, 90 there being an elongated recess between them, as shown. This locking member is mounted so that the finger 36 normally projects partly over the adjacent track member 7 and the hook 37 projects entirely over 95 said track member and partly over the associated re-inforcing member 8. Near the front end of said member 8 a short length of angle iron 38 is permanently secured of a 100 length that it may pass between finger 36 and hook 37 and having one leg thereof extending vertically.

When the rack is located within the show case the roller 24, carried by the bell crank lever, is seated in one or the other of the recesses 105 15^a of disk 15 as shown in Fig. 4, and the roller 30 is seated in the recess 33. Any attempt to rotate the rack when in such position is insured against because of the locking action of the roller 30 against the 110 forward side of the recess 33. When the rack is moved to extreme front position the finger 36 passes by the upwardly projecting leg of the member 38 but hook 37 engages against the rear edge thereof turning the locking member 31 from the position shown in Fig. 4 to that shown in Fig. 3. This releases the roller 30 from the recess 33 and the rack may then be rotated. The 115 rotation of the rack forces roller 24 out of the recess 15^a in which it has been seated, the bell crank lever turning about its pivot 22 and moving the roller 30 over the curved edge 34 of the locking member. This position of the parts is shown in Fig. 3 and it 120 will be noted that when so positioned the member 38 is disposed between finger 36 and hook 37, absolutely insuring against any rearward movement of the carriage until such time as the rack has been moved so 125 130

that its rods 20 are parallel to the back of the case, in which position the roller 24 seats in a recess 15^a of disk 15 and roller 30 is moved back so that it comes into conjunction with the recess 33 in the pivotally mounted locking member 31. Spring 35 normally turns the locking member to free the finger 36 from the part 38 and the rack may then be moved back into the case with the garment holding rods 20 disposed parallel to the back of the case.

The spring 29 acting through links 26, 27 and 28 holds the roller 24 yieldingly in a recess 15^a with a considerable force. When the rack has been moved to the front of the case and then rotated the movement of the bell crank lever induced by such rotation carried these links from the position shown in Fig. 4 to that shown in Fig. 3; and while the direct pulling force of the spring 29 is increased the moment arm, to which this force is applied, has been considerably shortened. In the position of the part shown in Fig. 4 this moment arm is substantially the full length of the link 28 or at least the distance between the centers of its pivot points. In Fig. 3 this moment arm has been decreased due to the change of position of the link 28 relative to the line of force of the spring 29 and the force of pressure of roller 20 against the edge of the disk 15 is less than its force of pressure against the disk when seated in a recess 15^a. This is a desirable feature in devices of this type and is attained with the structure shown and described in my patent to which reference has heretofore been made. The decreased force of the roller against the edges of the disk 15 obviate any destructive cutting of the edges of the disk or of the periphery of the roller without requiring that either member be hardened to withstand the service to which it is subjected.

The construction shown and described is a complete and practically operative embodiment of my invention and one which has proved fully satisfactory in every respect in practice. Various modifications in the detail of the specific structure may be resorted to without departing from the invention which is defined in the claims appended hereto, and it is to be considered that the invention is comprehensive of all forms of structure coming within the scope of such claims.

I claim:—

1. In a device of the character described, spaced apart tracks, a carriage mounted to move back and forth on said tracks, a rack rotatably mounted on and carried by the carriage, a disk connected to and rotatable with the rack having recesses in its edges, a lever mounted adjacent the disk and having means at one end adapted to engage said recesses in the disk, a spring acting on the

lever to force said means against the disk, a locking member pivotally connected to and movable with the carriage at one side thereof, a second means carried by the lever engaging against the inner edge of said locking member, said locking member having a recess to receive said second means when said first means on the lever is engaged in a recess in the disk, said locking member at its outer edge having a spaced apart finger and hook projecting therefrom, and a rigid member connected to one of said tracks near one end thereof by which said finger is adapted to move and against which the hook is adapted to engage to move the locking member automatically into position to release said lever, substantially as described.

2. In a device of the character described, a carriage mounted for reciprocatory movements, a rack mounted for rotation on the carriage, a disk connected to and rotatable with the rack, said disk having diametrically opposed recesses in its edges, a bell crank lever pivotally mounted on the carriage, a roller at one end of the inner arm of said lever adapted to engage in a recess in the disk or ride on the edges of said disk, a spring associated with the lever for holding said roller against the disk, a second roller mounted adjacent the free end of the other arm of the lever, a locking member pivotally mounted on the carriage formed at its inner edge with a recess to receive the second roller and having an edge portion in front of the recess against which said roller may ride when out of the recess, a spring connected with the locking member tending to turn the same toward the lever, said locking member at its outer edge being formed with a finger at its front portion and a hook adjacent its rear portion, and a rigid member located near one end of the path of movement of the carriage by which said finger may pass but against which said hook engages to thereby turn the locking member to release the second roller on the bell crank lever from said recess in the locking member and free the disk and attached rack for rotation.

3. In combination, a carriage mounted for horizontal reciprocatory movements, a rack rotatably mounted on the carriage, a disk secured to and rotatable with the rack located directly over the carriage, a bell crank lever pivotally mounted on the carriage having a rearwardly extending arm and an outwardly extending arm, a roller mounted at the end of the rearwardly extending arm, said disk having diametrically opposed recesses in which the roller may seat, a second roller mounted adjacent the end of the outwardly extending arm, a link connected to the outwardly extending arm between the rollers and extending forwardly therefrom, a second link pivotally con-

nected at one end to the carriage and extending inwardly from its point of pivotal connection and pivotally connected at its opposite end to the free end of the first link, 5 a third link pivotally connected to the first and second links at their point of pivotal connection extending rearwardly over the outwardly extending arm of the bell crank lever, a coiled spring disposed between the 10 rear end of the third link and the carriage, a locking member pivotally mounted on the carriage at the end of the outwardly extending arm of the bell crank lever, having a recess at its inner edge to receive the second 15 roller, a spring acting on the locking member to turn the same inwardly toward said second roller, and fixed means against which the locking member engages when the carriage is moved to extreme position in 20 one direction for turning the locking member outwardly about its pivot to disengage the same from the second roller, substantially as described.

4. In combination, a carriage mounted 25 for reciprocation in a horizontal plane, a rack mounted above the carriage for rotation in a horizontal plane, a disk connected to the rack and rotatable therewith located immediately above the carriage, said disk 30 having recesses in opposite sides, a bell crank lever pivotally mounted on the carriage and including a rearwardly extending arm and an outwardly extending arm, a roller on the end of the rearwardly extending arm to bear against the disk or seat in a recess thereof, spring actuated means 35 connected with the outwardly extending arm of the lever for holding the roller against the disk or in said recesses, said means including elements whereby the pressure of the roller against the disk is less than the pressure thereof against the edges of the recesses, a pivotally mounted locking member mounted adjacent the end of said 40 outwardly extending arm of the lever, interengaging means between said locking member and outwardly extending arm for normally locking the lever against movement about its pivot, spring means normally 45 holding the locking member in engage-

ment with said interengaging means on the arm of the lever, and means for automatically moving the locking member to inoperative position on movement of the carriage to its extreme position in one direction. 55

5. In combination, a carriage mounted for reciprocatory movements in a horizontal plane, a pedestal extending upwardly from the carriage, a rod extending through 60 the pedestal, a rack fixed at the upper end of the rod, a disk having recesses in opposite sides fixed at the lower end of the rod, said disk being located over the upper side of the carriage, a bell crank lever pivotally 65 mounted on the carriage having a rearwardly extending arm and an outwardly extending arm, a roller at the rear end of the rearwardly extending arm to bear against the disk or seat in a recess thereof, a second 70 roller mounted on the outwardly extending arm adjacent its free end, spring actuated means connected with said outwardly extending arm including devices for causing the first roller to bear against the edges of 75 the disk with less pressure than it bears against the edges of a recess in the disk, a locking member pivotally mounted on the carriage adjacent the free end of said outwardly extending arm of the lever, said locking member having a recess in its inner edge and a curved forwardly extending edge portion in front of the recesses and also having a front outwardly extending finger and a rear outwardly extending hook 80 at its outer edge, spring means acting on the locking member to turn the same inwardly toward said second roller, tracks supporting the carriage and a fixed member connected with one of the tracks against 85 which said hook strikes on movement of the carriage to its extreme position in one direction, thereby turning the locking member about its pivot and causing said fixed member to be positioned between said finger 90 and hook, substantially as described. 95

In testimony whereof I affix my signature.

ANTHONY VANDERVELD.
